UNITED STATES PATENT OFFICE.

LEANDER F. ST. CYR, OF SPRINGFIELD, MASSACHUSETTS, ASSIGNOR OF ONE-HALF TO
WILLIAM J. ST. CYR, OF SPRINGFIELD, MASSACHUSETTS.

COMBINED TRUNDLE AND OPERATING-HANDLE THEREFOR.

1,356,023.

Specification of Letters Patent. Patented Oct. 19, 1920.

Application filed June 13, 1919. Serial No. 304,058.

To all whom it may concern:

Be it known that I, LEANDER F. ST. CYR, a citizen of the United States, residing at Springfield, in the county of Hampden and State of Massachusetts, have invented certain new and useful Improvements in Combined Trundles and Operating-Handles Therefor, of which the following is a specification.

10 This invention relates to trundles, for toy rolling hoops, and a handle for operating the same, and an object of the invention is to provide a trundle or hoop rolling handle which is comparatively simple in construction, and forms a support for carrying a plurality of articles such as flags, and pin wheels, to lend attractiveness to the handle structure.

15 A further object of the invention is to provide a hoop engaging portion for the handle comprising a pair of spaced spring tongues having a constricted entrance to the hoop receiving portion thereof for preventing accidental disconnection of the hoop and handle, and which tongues are spaced a sufficient distance to allow free unimpeded rotation of the hoop.

More specifically, the invention comprehends the provision of a handle for rolling toy hoops or trundles which has a standard attached thereto intermediate its ends upon the upper end of which standard a support is mounted adapted to turn a plurality of flags and pin wheels, which will fly and rotate respectively during the rolling of the hoop.

Other objects of the invention will appear from the following detailed description taken in connection with the accompanying drawings, forming a part of this specification and in which drawings:

Figure 1 is a front elevation of the improved handle showing it connected to a part of a hoop.

Fig. 2 is a side elevation of a handle showing it connected to a hoop.

Fig. 3 is a horizontal section on the line 3—3 of Fig. 2 illustrating the manner of connecting the handle and hoop.

Fig. 4 is a vertical section on the line 4—4 of Fig. 1 illustrating the manner of connecting the carrying support to the standard which is formed upon the handle.

Fig. 5 is a detail vertical section through

the support illustrating the manner of attaching the flags or pin wheels thereto.

Fig. 6 is a detail vertical section on the line 6—6 of Fig. 1.

Referring more particularly to the drawings, wherein like characters indicate like and corresponding parts throughout the several views, the rolling hoop or trundle is generically indicated by the numeral 10. This hoop is preferably made of round material so as to eliminate the provision of corners or edges in the hoop structure, allowing it to rotate freely within the hoop retaining portion 11 of the handle structure 12.

The handle structure 12 includes a straight bar 13 which normally rests in a horizontal plane during the rolling of the hoop and which has a hand grip 14 upon one end and the hoop engaging portion 11 upon its opposite end. The hoop engaging portion 11 comprises a collar or sleeve 15 which is mounted over the end of the bar or rod 13 and which sleeve or collar has a pair of flat spring tongues 16 and 17 formed upon and extending outwardly from its outer end. These resilient tongues 16 and 17 are bowed, adjacent their connection with the sleeve to provide a relatively wide space which receives the hook 10 therein to permit free and unimpeded rotation of the hoop.

Outwardly of the bulged portions of the tongues 16 and 17 they are curved inwardly to provide a constricted mouth as shown at 19, to prevent accidental disconnection between the hoop 10 and the handle 12. The outer free ends of the tongues 16 and 17 flare, forming leads which lead inwardly into the constricted mouth 19 for facilitating the positioning of the hoop 10 properly within the bulged portions of the tongue.

A standard 20 is formed upon the rod 13 of the handle structure 12 intermediate its ends, and this standard 20 has its upper end flattened, as shown at 21 to provide a support upon which and to which this supporting structure 22 is attached. The supporting structure 22 is attached by means of rivets or analogous fastening devices 23 to the horizontal upset end of the standard 20. The carrying support 22 is substantially the shape of an inverted U, providing a horizontal portion 24 and downwardly extending end portions 25 and 26. The down-

wardly extending end portions 25 and 26 are provided with transversely extending openings therein, the horizontal portion 24 being provided with a plurality of vertical openings extending therethrough adjacent its end. The vertical openings 27 in the horizontal portion 24 and the horizontal or transversely extending openings in the downwardly extending portions 25 and 26 are adapted to receive the stems or standards of flags or pin wheels therethrough, which stems are securely held in adjusted positions within the openings by means of set screws or thumb screws 28. In mounting the various devices in the openings in the carrying supports 22 it is preferable to mount pin wheels as illustrated at 29 upon the downwardly extending portions 25 and 26 while the staffs of flags are inserted through the vertical openings in the horizontal portions 24. The horizontal portion 24 is provided with an opening 31 formed centrally therein which communicates with a recess 32 formed centrally in the upper surface of the upstanding horizontal end portion 21. This opening 31 and recess 32 are adapted to receive therein the staff 33 of the flag as indicated at 34 which staff is held against accidental movement out of the opening and recess by means of a thumb screw 35. It is of course to be understood that any type of flags such as indicated at 30 and 34 may be connected to the carrying support 32 and also that flags may be attached to the depending portions 25 and 26 in lieu of the pin wheels 29 if it is so desired, or that any analogous type of device or toy may be attached to the carrying support 22 without departing from the spirit of this invention.

When rolling a hoop, the child or person rolling the hoop gets directly behind the same, pushes the hoop 10 in front of himself and the movement of the child and the handle structure 12 will create sufficient breeze to cause the flags 30 and 34 to flutter and the

pin wheels 29 to rotate, lending a pleasing appearance to the toy.

Changes in details may be made without departing from the spirit of this invention, 50 but;

I claim:

1. In a toy, an operating handle for hoops comprising a rod, hoop engaging means carried upon one end of said rod, a hand grip 55 upon the opposite end of the rod, a standard carried by said rod intermediate its ends, a carrying support upon said standard, and means for attaching a plurality of articles to said carrying support. 60

2. In a toy, an operating handle for hoops comprising a rod, a pair of resilient tongues carried by one end of the rod and bowed to form a bulged portion for engagement about a hoop, a standard carried by said rod, and 65 means for attaching a plurality of articles to said standard.

3. In a toy, the combination, of an operating handle for hoops comprising a rod, retaining means carried at one end of said 70 rod, a standard carried by said rod, a carrying support attached to the upper end of said standard and provided with a plurality of openings extending therethrough, and thumb screws carried by said carrying support for engagement with articles inserted into said opening to attach the said articles to the carrying support. 75

4. In a toy, an operating handle for hoops, comprising a rod, hoop retaining 80 means upon one end of said rod, a hand grip upon the opposite end of said rod, a standard formed upon said rod intermediate its ends, a carrying support attached to the upper end of said standard and provided 85 with a plurality of openings adapted to receive therethrough the carrying stems of articles, and means for preventing accidental removal of article carrying stems from said openings.

LEANDER F. ST. CYR.
